G. S. HALL,
APPARATUS FOR RADIATOR REPAIRING,
APPLICATION FILED MAY 22, 1919.

1,350,866.

Patented Aug. 24, 1920.

UNITED STATES PATENT OFFICE.

GEORGE S. HALL, OF CHICO, CALIFORNIA.

APPARATUS FOR RADIATOR-REPAIRING.

1,350,866.

Specification of Letters Patent. Patented Aug. 24, 1920.

Application filed May 22, 1919. Serial No. 298,980.

To all whom it may concern:

Be it known that I, GEORGE S. HALL, a citizen of the United States, residing at Chico, in the county of Butte, State of California, have invented certain new and useful Improvements in Apparatus for Radiator-Repairing; and I do declare the following to be a full, clear, and exact description of the same, reference being had to the accompanying drawings, and to the characters of reference marked thereon, which form a part of this application.

This invention relates to an improved apparatus or work table for the repairing of radiators, the principal object of the invention being to provide a table or bench so equipped that radiators may be handled thereon for repairing of leaks etc., and held in any desired position during the repairing operations.

Another object is to provide the table with a water tank in which a radiator may be placed, the latter being adapted to rest on a platform in the tank arranged for vertical movement, so that a leaky radiator placed on the platform and connected to a compressed air supply may be moved up or down to exactly determine the location of a leak therein, as indicated by the bubbles of air rising through the water.

I have also built my improved table so as to be a complete and portable unit for repairing radiators by including all necessary devices therein, such as compressed air tanks and pumps, fire-pots, etc., control-cocks for the air and gas etc., so that all that is necessary to place my apparatus in running order when installed in a repair shop, is to connect it up with the gas and water piping and the electric wiring of the shop.

At present, radiators are repaired in a very crude way. The leaks therein are oftentimes found by guesswork by immersing in a tank or pumping water there-through usually at a point in the shop some distance from where the torches and solder pots are kept. If necessary to set the radiator at an angle in order to properly solder the same at any point, it is propped up against the columns or wall of the shop while being so soldered. These crude methods necessitate a great deal of manual handling, which is not only tiring to the me-

chanics, the radiators being somewhat heavy, but results in a slow job and great loss of time, and consequently is an item of considerable expense to the owner of the vehicle from which the radiator was taken. These disadvantages I have eliminated with the use of my improved table in which, as heretofore stated, I have arranged every thing necessary for the complete repairing of the radiator, without taking the same to any other part of the shop.

As a further object, I have produced a simple and relatively inexpensive device and one which will give eminently satisfactory results.

These objects I accomplish by means of such structure and relative arrangement of parts as will fully appear by a perusal of the following specification and claims.

On the drawings similar characters of reference indicate corresponding parts in the several views.

Figure 1 is a side elevation of my improved table.

Fig. 2 is a top plan view thereof.

Fig. 3 is a longitudinal section taken relatively on a line 3—3 of Fig. 2.

Fig. 4 is a fragmentary section taken on a line 4—4 of Fig. 2, showing a removable radiator supporting standard.

Referring now more particularly to the numbers of reference on the drawings, the numerals 1 and 2 denote a pair of table tops of any suitable dimensions, and spaced apart for the positioning of a rectangular open-topped water tank 3 therebetween. Side members 4 connect the table tops and sustain the tank, the entire unit being supported on legs 5 of a suitable height. Centrally positioned in the bottom of the tank 3 and extending a suitable distance therebelow is a cylinder or well 6 in which is adapted to slide a hollow guide or plunger 7, the same being held from turning in the well by means of a vertical lug 8 running the full height of the well and fitting into a recess 9 in the plunger 7. The same result may also be obtained by making the well and plunger square in cross section.

A drain cock 3^a is set in the bottom of the tank 3 to drain the same.

On the plunger is secured a vertical sleeve 105 10, in which is turnably mounted a post 11

which supports and has secured thereto on its upper end a platform 12 of any desired and suitable shape and construction.

A pulley 13 is mounted in the plunger 7 centrally thereof, the top of the plunger being provided with slots 14 therein for the passage of a cable 15 therethrough, which cable is secured to the top of the cylinder at one end, then passes through pulley 13 and then around pulleys 16 arranged to carry the cable above the line of the water in the tank 3, running thence to and being wound around a shaft 17 secured to and extending outside the frame 4. The shaft 17 is turned by means of a hand wheel 18 thereon, and is adapted to be held in any desired position by some such means as a pawl and ratchet 19.

Low pressure and high pressure air tanks 20 and 21 respectively are located under the table 2 and the tank 3, the high pressure tank being supplied by means of an air pump 22 driven by an electric motor 23. The low pressure tank is filled to a desired pressure from the high pressure tank by means of suitable piping therebetween controlled by a valve 24. Behind the tank 3 is a dial and control board 25 having air gages 26 thereon for the air tanks and gas and air controls 27 and 28 respectively for blow torches 29, the primary air control to the valves 28 from the high pressure tank being had by means of a valve 30. One or more fire pots 31 are also included in the equipment, these being connected with a gas supply. Positioned under the table 1 to project through the wall 4 are a plurality of parallel bars 32 arranged in staggered order. These bars are slidable outwardly from the wall 4, and also pass through a guide or supporting member 33 positioned behind the front wall 4 and under the table 1. Stop lugs 34 are provided on the bars so as to prevent them being pulled out farther than the guide 33.

On the outer front edge of the table 1 are a plurality of vertically positioned slotted holes 35 in which fit removable pins 36 secured to and extending down from standards 37. These pins are provided with cross lugs 38 on their lower ends, adapted to pass through the slotted holes 35. Brace brackets 39 are mounted to the standards 37 and are adapted to rest on the table 1 to the rear of the standards, the slotted holes 35 being positioned parallel to the normal position of the brackets 39 and the lugs 38 transversely thereof, so that when the standards are placed in position, a half-turn is necessary to bring them to their normal position, and the lugs 38 then rest across the narrow portion of the holes 35, thus effectually preventing the pins 36 being forced out of the holes when a weight is thrown on the standards.

In the operation of the device, when a leaky radiator is to be repaired, it is first placed on the platform 12, the tank 3 being

filled with water and the platform positioned so that the radiator is entirely submerged. Air from the low pressure tank 20 is then admitted to the radiator and the general location of the leak will be evident 70 from the resultant bubbles of air rising through the water. By then turning the hand wheel 18 to raise the platform 12, the radiator may be gradually raised from the water till the bubbles cease, at which point 75 in the thickness of the radiator it is evident the leak is located. By turning the radiator by hand, this being possible by means of the turnable post of the pedestal, the point of leakage may be brought within easy reach 80 of the mechanic. This leak may then be soldered while still retaining the radiator on the platform, or it may be taken off and placed on either one of the tables 1 and 2.

If necessary to set the radiator at an angle 85 for the purpose of properly soldering a leak or otherwise making repairs thereto, a couple of the bars 32 are pulled out, the great number of these making it an easy matter to select any two to give any desired angle, so 90 that the radiator may rest thereon, and also lean against the standards 37.

Thus, from the foregoing description it will be readily seen that I have produced such a device as substantially fulfills the object of the invention as set forth herein.

While this specification sets forth in detail the present and preferred construction of the device, still in practice such deviations from such detail may be resorted to as 100 do not form a departure from the spirit of the invention, as defined by the appended claims.

Having thus described my invention what I claim as new and useful and desire to set 105 out for Letters Patent is:—

1. In a work bench arranged and equipped for the repair of radiators thereon, a plurality of independent horizontal bars slidably mounted in the side of the bench and 110 arranged to be pulled out a predetermined distance, and removable uprights on the top of the bench projecting upwardly therefrom at the edge thereof adjacent the bars.

2. In combination with a work bench arranged and equipped for the repair of radiators thereon, means in the bench whereby a radiator may be tilted at any angle relative to the table and maintained in that position, such means including a plurality of 120 horizontal and independent bars slidably mounted in the side of the bench in spaced order both horizontally and vertically and arranged to be pulled out a predetermined distance, any two being adapted to sustain 125 the weight of a radiator.

3. In a work bench arranged and equipped for the repair of radiators thereon, a plurality of independent horizontal bars slidably mounted in the side of the bench and 130

arranged to be pulled out a predetermined distance, uprights on the top of the bench projecting upwardly therefrom at the edge thereof adjacent the bars, and means for holding the uprights in a rigid vertical position while permitting them to be easily removed.

In testimony whereof I affix my signature in presence of two witnesses.

GEORGE S. HALL.
